UNITED STATES PATENT OFFICE.

JOSEPH H. BOURGON, OF DETROIT, MICHIGAN, ASSIGNOR TO THE STUDEBAKER CORPORATION, OF SOUTH BEND, INDIANA, A CORPORATION OF NEW JERSEY.

BODY CONSTRUCTION.

Application filed June 21, 1926. Serial No. 117,413.

This invention relates to body constructions, and particularly to auxiliary seats therein adapted to be folded and swung to a position adjacent the dash when not in use.

5 The principal object of the present invention is to provide an auxiliary seat which is supported by a single pivoted leg.

Another object is to provide an auxiliary seat supported by a single leg positioned at 10 one of the forward corners of the seat bottom, whereby there is a minimum of obstructions below said seat.

Another object is to provide an auxiliary seat for an automobile, said seat being provided with a single leg secured to the forward edge of the bottom thereof and pivotally supported at its lower end on one of 15 the sills of said body.

Another object is to provide an auxiliary seat for an automobile body, said seat comprising a bottom having a back pivotally secured thereto, and a single supporting leg rigidly secured thereto and pivotally supported in the plane of the floor of said body, whereby said back may be folded over 20 said bottom and said bottom and back may be swung as a unit to a position below and in the plane of the instrument board of said body, leaving the floor clear and unobstructed thereby.

Another object is to provide a new and novel means for pivotally supporting a leg of an auxiliary seat in the plane of a floor, comprising a slot in the floor for receiving 25 said leg when the seat is in folded position, bearings for pivotally receiving the lower end of said leg below the surface of the floor, and an articulated plate pivotally connected to said leg whereby to close said slot 40 when said leg is in upright or operative position.

A further object is to provide a slotted frame the upper surface of which is positioned flush with the surface of the floor of 45 a vehicle, said frame being provided with bearings for pivotally supporting the lower end of a leg of a folding seat, said leg being positioned so that when the seat is in folded position the leg is received within the slot 50 and the upper surface of the leg is flush with the surface of the floor, and a plate pivotally secured at one end to the leg and pivotally supported at its opposite end on a swinging link, whereby when said seat is

swung into operative position the plate 55 closes the slot in said frame.

The above being among the objects of the present invention, the same consists of certain features of construction and combinations of parts to be hereinafter described 60 with reference to the accompanying drawings, and then claimed, having the above and other objects in view.

In the accompanying drawings, in which like numerals refer to like parts throughout the several different views:

Figure 1 is a fragmentary perspective view of the front compartment of an automobile body in which a seat incorporating the present invention is shown in folded 70 position beneath the instrument board thereof.

Figure 2 is a perspective view of the seat illustrated in Figure 1, shown in unfolded or operative position, and showing a partially broken view of the means for supporting the lower end of the seat leg.

Figure 3 is a perspective view from below and from the rear of the frame for the seat shown in the preceding views, showing the 80 manner of securing the supporting leg thereto.

Figure 4 is a fragmentary perspective view of the bearing frame which pivotally supports the lower end of the seat leg, shown 85 supported in the sill of the body, the near face of the frame being removed to more clearly show the construction of the same.

Figure 5 is a fragmentary perspective view similar to Figure 4, with the exception 90 that a fragment of the seat leg and the slot concealing plate are shown in the positions which they assume when the seat is in open or operative position.

Figure 6 is a fragmentary perspective 95 view of the parts shown in Figure 5, with the exception that more of the seat leg is shown, the parts being in the position which they assume when the seat is in folded or inoperative position, corresponding to the 100 position of the seat as shown in Figure 1.

Figure 7 is a perspective view of the leg supporting frame.

Auxiliary or folding seats are commonly used in automobile bodies of different types, 105 but perhaps the greatest number of them are used in the so-called "coach" type of automobile body which is usually built to provide

seats for five passengers, three in the back of the body and two in front, with but a single door on each side of the body, in line with the front seats, for the ingress and egress of the passengers. Inasmuch as the front seats normally block the path of the passengers to and from the back seats through the door, it is necessary that the front seats be constructed so as to be capable of being moved out of line with the door so as to permit such movement of the passengers. The front seats thus provided for "coach" type bodies are commonly known as auxiliary seats because of the fact that they may usually be folded up and swung forward out of the way to allow passengers from the back seat to leave, or to allow them to enter the door, or they may be left in such folded position when not being occupied by a passenger. As far as I have been able to determine, all such seats have, before the present invention, been equipped with two legs at the forward edge thereof, the lower ends of such legs being pivotally supported on brackets extending above the plane of the floor. Some types of these seats have been equipped with one or more rear supporting legs in addition to the forward legs, but because of the "close coupled" construction of the coach type of body such rear legs are usually dispensed with in those types of bodies and the pivotal supports for the front legs constructed to hold the seat in proper upright position without additional supports, thereby allowing the passengers in the back seats to put their feet under the front seats and effecting an increase in the leg room. Inasmuch as the pivot point of the seat legs is above the surface of the floor, when the seats are folded up the legs thereof form an obstruction on the surface of the same, and the elimination of such obstruction is one of the objects of the present invention, as well as eliminating one of the two legs conventionally used, thereby providing a maximum of unobstructed space beneath the seat when in operative position.

In the present invention a seat is employed comprising a seat bottom 11 to which a seat back 12 is pivotally secured. As shown in Figure 3, the seat bottom 11 is built up on a frame 13 which is provided adjacent its rear edge with brackets 14 to which the frame 15 for the seat back 12 is pivoted at 16, the pivotal joint being such that the back frame 15 cannot be moved further back in relation to the seat bottom frame 13 than is shown in Figures 2 and 3, although it may be folded forwardly into contacting relation therewith as indicated in Figure 1. The single seat shown is for the right hand front seat as indicated in Figure 1, and for this particular seat its single leg 17 is positioned at the forward right hand corner thereof, the leg 17 being secured to the seat frame 13 by means of the divergent flange arms 18 which extend

across the bottom of the same, as indicated in Figure 3, and are secured thereto by screws, such as 19, or by other suitable means.

The lower end of the leg 17 is supported in a frame 20 comprising rectangular sides and a top plate provided with a longitudinally extending slot 21, the margins of the top plate extending over the sides thereof to provide flanges for supporting the same from the body sill 22 in which it is received. Adjacent one end of the slot 21, bearing valves 23 are formed on the side walls of the frame 20, and bearing caps 24 are recessed in said side walls for completing the bearing. These bearings receive the ends of the pin 25 which extends transversely through the lower end of the leg 17 and about which the seat is swingable. The leg 17 with the pin is introduced into the bearing 23 by removing the caps 24 and dropping the leg with the pin 25 into place, and thereafter replacing the caps 24 and securing them in place by screws such as 26 which pass therethrough and into the frame 20.

The seat when swung into operative position, is held in that position by the leg 17 abutting against the adjacent end of the slot 21, it being held from swinging into inoperative position by reason of the fact that substantially all of its weight overhangs rearwardly of the leg 17 and therefore tends to swing the leg further against the end of the slot 21. When the seat is tipped forwardly about the pin 25, into inoperative position, the leg 17 drops down into the slot 21, the bearings for the pin 25 being so positioned that the then upward face of the leg 17 lies flush with the surface of the top plate of the frame 20 and therefore flush with the floor of the body, thereby eliminating any substantial projection or depression on the floor of the body. The leg 17 is held from dropping any further into the slot by the front edge of the seat bottom which rests on the floor when the seat is in inoperative position. As illustrated in Figure 1, before the seat is swung into inoperative position, the back 12 is folded over on the bottom 11 and the seat as a whole is then tipped forward and comes to rest below the instrument board 27, thereby leaving the floor of the body substantially clear of the same.

In order to close the slot 21 when the seat is in open or operative position, a plate 28, of slightly less width than the slot 21, is pivotally secured at 29 to the lower end of the leg 17 and extends forwardly therefrom to a point adjacent the forward end of the slot 21, when the seat is in operative position, and is there pivotally supported at 30 on the upper end of a link 31 which extends downwardly therefrom and is pivotally supported on the pin 32 which in turn is supported in the boss 33 on the inner face of

one of the sides of the frame 20. The plate 28 is, as shown, so positioned as to be flush with the upper face of the frame 20 when the seat is in operative position, and substantially closes the slot 21 which would otherwise be open. When the seat is swung into closed or inoperative position, the plate 28 and link 31 swing down to a position below the leg 17 as shown in Figure 6.

10 It will be noted that in the construction shown and described, the frame 20 is supported by the body sill 22, which offers a very substantial seat supporting means and offers no interference to the removal of floor 15 boards, carpets and the like.

Formal changes may be made in the specific embodiment of the invention described without departing from the spirit and substance of the broad invention, the 20 scope of which is commensurate with the appended claims.

What I claim is:

1. In combination with an automobile body, an auxiliary seat therefor comprising a bottom and a back pivotally secured thereto, a single supporting leg rigidly secured to said seat and pivotally supported in bearings below the surface of the floor, a slot in said floor for receiving said leg when said 25 seat is in folded position, and an articulated plate pivotally connected to said leg and closing said slot when said seat is in operative position.

2. In combination with an automobile body provided with a folding seat having a single supporting leg, means for pivotally supporting the lower end of said leg comprising a slotted frame supported in the plane of the floor of said body, said frame 30 provided with bearings for receiving the lower end of said leg, and a plate pivotally

secured at one end to said leg and at the other end to a pivoted link supported by said frame whereby when said seat is swung into operative position said plate closes the slot 45 in said frame.

3. Means for supporting a folding seat in an automobile body, comprising a single leg for said seat, a frame secured in the plane of the floor of said body, a slot in said frame through which said leg projects, bearings in said frame for pivotally supporting the lower end of said leg, and an articulated plate secured to and movable with said leg, said leg being received within said slot and 50 closing the same when said seat is in folded position, and said plate closing said slot when said seat is in unfolded position.

4. In combination with an automobile body having a sill and floor boards, a folding seat for said body provided with a single leg, a frame carried by said sill independently of said floor boards, a slot in said frame in which said leg is received when said seat is in folded position, means for pivotally supporting one end of said leg in said frame, and a plate operated by movement of said leg closing said slot when said seat is in open position.

5. In combination with an automobile body provided with a floor, a folding seat for said body, a leg for said seat, means for pivotally supporting said leg below the surface of said floor, a slot in said floor for receiving said leg when said leg is in folded 70 position, and a plate movable by said leg closing said slot when said leg is in upright position.

Signed by me at Detroit, Michigan, U. S. A., this 14th day of June, 1926.

JOSEPH H. BOURGON.
